UNITED STATES PATENT OFFICE.

HORACE W. MESSE, OF TROY, NEW YORK, ASSIGNOR OF TWO-THIRDS TO
MANVILLE & CLARK, OF SAME PLACE.

SHIRT.

SPECIFICATION forming part of Letters Patent No. 268,424, dated December 5, 1882.

Application filed December 19, 1881. (No model.)

To all whom it may concern:

Be it known that I, HORACE W. MESSE, of the city of Troy, county of Rensselaer, and State of New York, have invented a new and useful Improvement in Bosom-Shirts, of which the following is a specification.

My invention relates to bosom-shirts, and a manner of making the bosom automatically adjustable to the motion of the body when worn.

My invention consists in the combination, with a shirt-front and a shirt which opens at the back and has at the front a continuous neck-band, of a bosom that is unattached to the shirt-front proper, but which at each of its sides has staying-pieces, which connect the bosom with the side sleeve-seams and the lower sides of the yoke where the latter joins the sleeves, the object being to use a shirt-bosom which will be secured to neck of the wearer by an attached collar alone, and the bosom left free for automatical vertical adjustment to the motion of the body.

The accompanying drawing, forming a part of this specification, illustrates bosom-shirts containing my invention, and the several parts as made and combined to produce it are indicated by letter-reference, and described as follows:

The letter E designates the body proper of the shirt at its front; B, the bosom; C C, the side staying-pieces, which are each attached to the side of the bosom and to the sleeve-seam S'', and the lower yoke-seam, S'. The letter A indicates the yoke; N', the neckband of the shirt; N'', the bosom neckband, the neckband of the shirt being shown by a dotted line at Y, where continued down below the bosom neckband. The letter T indicates a bosom-tab, and F a

button upon the shirt-body for attaching the bosom to the shirt, when desired. The bosom B is free from the shirt-front proper throughout its whole length, and is only connected with the shirt indirectly by means of the side facing or staying pieces, before described. The top of the bosom is free from the shirt-front proper, as relatively shown in my application for a patent for a similar improvement, filed September 21, 1881, but differs from that in the fact that the bosom proper is wholly unattached to the shirt-front, and that no tabs are used on the bosom neckband to connect with the neckband of the shirt at the sides of the band, and also in the fact that the bosom herein is secured as against a free vertical as well as horizontal adjustment by connecting the attached facing to the sleeve-seam and the yoke-seam on an angle.

The bosom thus made and arranged will adapt itself to the use of a longer or shorter collar, and the latter, when attached to the bosom neckband at the front, will keep the latter in place and leave the bosom free to adjust itself to the motions of the body.

Having thus described my invention, what I claim, and desire to secure by Letters Patent, is—

The combination, with the body of shirt provided with a button at F, of the bosom B with the bosom neckband N'', side staying-pieces, C C, and bosom-tab T, attached to the body of the shirt, in the manner as described.

Signed at Troy, N. Y., this 9th day of December, 1881.

HORACE W. MESSE.
